HENRY TIEDEMANN, OF NEWARK, NEW JERSEY, ASSIGNEE TO SPLITDORF ELECTRICAL COMPANY, OF NEWARK, NEW JERSEY.

IMPULSE STARTING-COUPING.

1,295,633.

Specification of Letters Patent. Patented Feb. 25, 1919.

Application filed July 15, 1918. Serial No. 245,060.

To all whom it may concern:

Be it known that I, HENRY TIEDEMANN, a citizen of the United States, residing at Newark, in the county of Essex and State 5 of New Jersey, have invented certain new and useful Improvements in Impulse Starting-Couplings, of which the following is a specification.

My invention relates to a coupling device 10 of the impulse type to be used in connection with internal combustion engines, which at the time of starting ordinarily have a comparatively low rotative speed at the instant the engine is going over compression. Where 15 a magneto is used for ignition the slowing down of the engine as it goes over compression causes the magneto to deliver a weak spark, which makes hard starting, especially so where a poor mixture is obtained and the 20 fuel is of low gravity test and not easily vaporized. As soon as the engine is started, the magneto supplies ideal ignition and in order, therefore, to overcome the objection of hard starting it has become quite common 25 to use a device which will accelerate the speed of the rotating part of the magneto at the time the engine is going over compression. By supplying a device of this character sparks are obtained at the instant of 30 starting which are equivalent to those obtained under ordinary running conditions or an even better spark may be obtained.

In general, an impulse starting coupling 35 consists of a driven member fastened to the operating shaft of the ignition generator, a driving member associated with the driven member and having a resilient member forming a driving connection between the driving and driven members. Some means 40 is provided to retard or stop the driven member and consequently the operating shaft of the ignition generator from rotating over a predetermined period, then releasing the driven member which, acting under the 45 force of the energy stored in the resilient member, due to the driving member having been driven forward of the driven member, is given a sudden impulse forward, thereby producing a hot spark.

50 It is the object of my invention to provide a simple, inexpensive, positively acting device for controlling the driven member to produce the impulse.

In describing my invention, I have utilized

a type of coupling shown and described in 55 Patent #1,226,933, issued May 22, 1917, to Fred B. Williams, but since my invention is directed to means for controlling the driven member to get the impulse, and not to the details of the coupling itself, the construction 60 of the coupling will only be briefly herein referred to, as the operation of these devices is now well understood.

In the drawing which forms a part of this specification, Figure 1 is a part end view of 65 a magneto showing the coupling in position on the operating shaft and the controlling means in the "off" or out of engagement position with the driven member.

Fig. 2 is a view similar to Fig. 1 but with 70 the controlling means in the "in" engagement position with the driven member.

Fig. 3 is a view of the driven member with the impulse and buffer springs in place, together with the stud of the driving member 75 in operative position. The end of the ignition generator shaft is also shown.

Referring now to the details, in which like numbers refer to corresponding parts in the various views, 1 is a plate mounted on the 80 end of the ignition generator, through which the operating shaft 2 projects. The driven member 3 is held in operative position on the operating shaft 2 by the usual taper and key (not shown) and nut 4. The driven member 85 3 carries an impulse spring 5 which abuts at one end against the stop 6 attached to the member 3 and at the other end against the stop 7 carried on the driving member 8. Between the stops 6 and 7 is a buffer spring 9 90 which serves to take the shock as the driven member rapidly overtakes the driving member 8 after the driven member has been released and sent forward under the force of the spring 5, all as fully explained in the 95 said Williams patent. The driving member 8 has a cross slot 10 to receive a driving means attached to the engine. The driving member also has cams 11 and 12 for a purpose which will be hereinafter explained.

100 Mounted on the plate 1 is a pawl 13 pivoted at 14. The pawl 13 can be shifted so that the nose 15 engages notches 16 and 17 in the driven member 3. On the top side of the pawl are two depressions or recesses 18 and 19, with a rounded end projection 20 separating the said depressions or recesses. Carried on the plate 1 is a resiliently mount-

- ed member which preferably takes the form of a cylinder 21 within which is a spring 22 that acts on a plunger 23, preferably in the shape of a ball. The spring 22 is put under 5 more or less compression stress by an adjusting screw 24. The resiliently mounted member is carried on the plate 1 in such a manner that its line of action, when the pawl is either in the "in" or "out" position, is in 10 line with the pivot 14 so that as the pawl 13 is moved to either the "in" or "out" position the plunger 23 will be either in the recess 18 or 19, the projection 20 being so formed that it will not rest on it.
- 15 In the operation of my device the operating means, such as a rod or cord of some sort is attached to the pawl 13 by means of the hole 25. A pull on the rod will move the pawl 13 so that the nose 15 engages the 20 flange of the driven member 3. As the driving and driven members advance together the nose 15 of the pawl 13 will finally drop into either the notch 16 or 17, under which condition the driven member 3 is held from 25 rotation and the driving member 8 advances until either one of the cams 11 or 12 engages the pawl 13 along the line 26, as shown in Fig. 2. Further rotation of the driving member 8 causes either the cam 11 or 12 to 30 raise the nose 15 of the pawl 13 out of engagement with either one of the notches 16 or 17 and as soon as the nose 15 is clear from said notches the driven member 3 with the shaft 2 is thrown rapidly forward by the 35 impulse spring 5 producing a spark, as heretofore described. Assuming that the engine immediately "picks up" the cams 11 and 12 will soon hit the nose 15 hard enough to throw the pawl 13 to the position in Fig. 1 40 where it is held by the plunger dropping into the recess 18 ready for the next start.
- I have found the above described construction very positive in its action and while I have shown one type of resiliently mounted 45 member for acting in the pawl, I do not wish to be limited to the exact form of this member or the pawl itself, other than is limited by the scope of the appended claims.
- Having thus described my invention what 50 I claim is:
1. In an impulse starting coupling for an ignition generator having an operating shaft, a driven member fastened to said shaft, a driving member associated therewith, a resilient member forming a driving connection between the driving and driven members, a pivoted pawl stop for said driven member and shaft, means operated by the driving member for engaging the pawl 55 stop to remove it from engagement with the driven member and a latch acting substantially in line with the pivotal point of the pawl for holding the pawl "in" or "out" of engagement with the driven member after having been so positioned.
2. In an impulse starting coupling for an ignition generator having an operating shaft, a driven member fastened to said shaft, a driving member associated therewith, a resilient member forming a driving connection between the driving and driven members, a pivoted pawl stop for said driven member and shaft, means operated by the driving member for engaging the pawl stop to remove it from engagement with the driven member and a latch of the plunger type having the plunger acting on and substantially in line with the pivotal point of the pawl for holding the pawl "in" or "out" of engagement with the driven member after having been so positioned.
3. In an impulse starting coupling for an ignition generator having an operating shaft, a driven member fastened to said shaft, a driving member associated therewith, a resilient member forming a driving connection between the driving and driven members, a pivoted pawl stop for said driven member and shaft, means operated by the driving member for engaging the pawl stop to remove it from engagement with the driven member and a latch consisting of a casing carrying a spring operated plunger acting substantially in line with the pivotal point of the pawl for holding the pawl "in" or "out" of engagement with the driven member after having been so positioned.
4. In an impulse starting coupling for an ignition generator having an operating shaft, a driven member fastened to said shaft, a driving member associated therewith, a resilient member forming a driving connection between the driving and driven members, a pivoted pawl stop for said driven member and shaft, means operated by the driving member for engaging the pawl stop to remove it from engagement with the driven member, said pawl having two recesses closely adjacent each other and a latch of the plunger type having the plunger seated in either one or the other of said recesses to hold the pawl "in" or "out" of engagement with the driven member after having been so positioned.
5. In an impulse starting coupling for an ignition generator having an operating shaft, a driven member fastened to said shaft, a driving member associated therewith, a resilient member forming a driving connection between the driving and driven members, a pivoted pawl stop for said driven member and shaft, means operated by the driving member for engaging the pawl stop to remove it from engagement with the driven member, a latch consisting of an adjustable resiliently mounted member with means on said pawl to positively position said member in either one of two positions of engagement therewith to hold

the pawl "in" or "out" of engagement with the driven member after the pawl has been so positioned.

6. In an impulse starting coupling for an ignition generator having an operating shaft, a driven member fastened to said shaft, a driving member associated therewith, a resilient member forming a driving connection between the driving and driven members, a pivoted pawl stop for said driven member and shaft, means oper-
ated by the driving member for engaging the pawl stop to remove it from engagement with the driven member, a latch consisting of a casing carrying an adjustable 15 spring operated plunger, recesses on the upper side of said pawl to receive said plunger whereby the pawl is held either "in" or "out" of engagement with the driven member after having been so positioned. 20

In witness whereof, I affix my signature.
HENRY TIEDEMANN.
